DOOR HANGER

Murrell R. Spence, North Hollywood, and
Noah O. A. Hayman, Alhambra, Calif.

Application March 4, 1950, Serial No. 147,674

3 Claims. (Cl. 16—105)

1

This invention relates to sliding doors and has particular reference to improvements in suspending devices for such doors.

One of the difficulties commonly encountered in the use of sliding doors, particularly in wooden doors mounted within wooden framing, is that the material of the door or of the framing may warp thereby to cause the door to stick and so to render the opening and closing operations thereof difficult. Another condition commonly encountered in such wooden residential sliding door constructions is the difficulty of relatively adjusting the door on the suspension mechanism as required for smooth and easy operation of the door. Another difficulty in such residential sliding doors as commonly used is that it is impossible to adjust the suspension mechanism after the door framing has been completely assembled and that for this reason the door must be mounted in position and adjusted before the finished lumber is placed on the studding of the wall.

In view of the foregoing, it is the general object of the present invention to provide a door hanger combination so constructed that the door may be adjusted vertically without removing it from its track. It is a further object of the invention to provide a device in which the door frame may be completely finished before the door is hung and the position of the door correctly adjusted and readjusted at any time without having to tear down the finished door framing or removing the door. Another object is to provide a door supporting mechanism which, once correctly adjusted, will afford the door sufficient freedom of movement relative to the supporting mechanism to insure easy and unhampered operation of the door.

These objects and the advantageous features of the invention will be better understood from the following detailed description and by referring to the accompanying drawings in which a preferred form of the invention is illustrated. In the drawings:

Fig. 1 is a cross-sectional, end elevational view of a door framing constructed in accordance with the present invention and illustrating the improved means of maintaining a door suspended within this framing;

Fig. 2 is a substantially corresponding, fragmentary view of one upper corner of a door showing members of the suspension mechanism of the invention mounted in position thereon;

Fig. 3 is a side elevational view of the upper portion of the suspension mechanism shown in Fig. 2;

2

Fig. 4 is a reversed side view of the lower portion of the suspension mechanism of Fig. 2; and
Fig. 5 is a fragmentary plan view of the beam on which the door is hung.

5 The framing of the door includes conventional side members or stiles 1, 2, to the top of which are secured headers 3, 4 in any ordinary well-known manner. The adjacent upper corners of these headers are shown recessed to support 10 therein track suspension members 7, 8 which are shown sufficiently spaced apart to receive therebetween a channeled beam 10 forming the track on which the door of the invention is mounted to roll. This beam is by means of screws 11, 12, 15 shown rigidly secured in position between the members 7, 8. From the upper horizontal flange 10a of the beam 10 may in addition be extruded lips 13 which are bent horizontally in the opposite direction to rest on the member 7, to which these 20 lips may be secured by means of screws 14. When so constructed, it is seen that the track may be held rigidly supported on the members 7, 8, without any danger of sagging, spreading or otherwise getting out of adjustment. When such lips 25 are provided the screws 12 may be omitted and the beam mounted on the members 7, 8 after the rough framing is completed.

It is customary to provide a hanger attached to the top surface of the door near each end of this 30 surface and such hanger is in the drawings shown to include an upper bracket 21 on which rollers 20 are rotatably secured and a lower bracket 30. As illustrated, it is preferred to mount a pair of rollers 20 on each bracket but it 35 is to be understood that a single roller may be substituted, if preferred. The lower portion of the bracket 21 is, as best indicated in Fig. 1, shown upwardly folded to provide a groove 22 of a size snugly to receive therein the downwardly 40 bent flange 31 of the lower bracket 30, which latter is shown mounted in position on the top surface of the door 32 as by means of screws 33. It is important to note that the lower portion of the bracket 21 is shown offset to bring these 45 interengaging portions of the brackets 21 and 30 directly beneath the rollers 20. The purpose of this method of suspending the door is to be able to mount the door brackets 30 in position on the door and then, after the rollers have been placed 50 on their track to seat the flanges 31 in the grooves 22 of the upper brackets.

The lower bracket 30 is for this purpose shown made with a series of equidistant perforations 35 in the wall upwardly extending from the base 55 thereof and because the bottom edge of the flange

31 extends to a position in registration with the center line through these perforations, it becomes necessary to sink notches 36 into this bottom edge in axial alignment with the perforations. Similar notches 25 are sunk into the bottom surface of the bracket 21 for registration with the perforations 35 when the bracket 30 is hung on the bracket 21, whereupon an element such as a pin, screw or cotter key 40 is inserted through one of these perforations for the purpose of locking the brackets against relative longitudinal displacement. It is important to note that the spacing between the notches 25 varies slightly from the spacing between the perforations 35 of the bracket 30. This is done in order that one bracket may be adjusted longitudinally relative to the other in order to be correctly positioned on the supporting beam 10 and the element 40 subsequently inserted to lock the part together, as will be more fully described presently. The parts are for this purpose shown provided with four groups of perforations and notches, but it is to be understood that additional notches may be provided for finer adjustment, if found desirable.

Another important feature of the invention is that the interengaging portions of the two brackets are not arranged in parallel relation to the track and the upper surface of the door but are shown somewhat inclined in one direction. This is done in order to enable the builder to mount the door in correct vertical relation to the floor and to the upper framing of the doorway. If, for example, it is found that the door hangs too close to the floor, it is merely required to remove the element 40 and to move the brackets 21 lengthwise relative to the bracket 30 until the proper elevation is obtained, whereupon the element may be reinserted through the notches and perforations corresponding to this position of adjustment. The angle of inclination of the parts should, of course, be calculated to provide any desired amount of adjustment. Referring now to Fig. 3, it is noticed that the upper edge 26 of the lip 23 is shown somewhat upwardly curved toward the center thereof. This is done in order that, when the door has been completely adjusted as above described, the door bracket 30 may retain some freedom of rocking movement on the curved surface 26. It has been found in actual practice that, when so mounted, the operation of opening and closing the door will be greatly facilitated.

It was above stated that the door of the present invention may be mounted in position and adjusted after the door framing has been assembled. In practice, the door framing generally includes stops 42 and 43 mounted on the stiles 1, 2 of the framing and horizontally disposed stops 44, 45 attached to the headers 3, 4 thereof.

It is common practice and it is preferable to mount one of these horizontal stops as, for example, stop 44 permanently in position and to fasten the stop 45 on the header by means of suitable screws 46 in order that, if due to warping it should be found that the door commences to stick, it will be possible slightly to adjust the position of the stop 45. The stops 43 are often similarly mounted for the same reason. By reference to Fig. 1 of the drawings, it is readily seen that, when the stop 45 is removed from the framing, it is possible to hang the door by placing the flange 31 within the groove 22 of the bracket 21 and to insert the element 40 after these suspending members have been relatively adjusted whereupon the stop 45 may be put back

in position. It is also to be noted that it is possible in the same manner to readjust the door mounting at any later time to vary the distance of the bottom of the door from the floor, as when carpets and rugs are to be laid on the floor; also that the door may be removed and remounted at any time as may be required for repairs or replacement by merely detaching the stop 45.

While we have herein described a preferred form of the invention it is to be understood that modifications may be embodied which fall within the scope of the claims hereto appended.

We claim:

1. A door hanger for supporting a door within a frame having a channeled beam mounted therein, said door hanger including a lower bracket having a base mountable on top of the door and a wall rising from said base, the upper end of said wall being folded to form a pendent flange parallel with the wall, the upper surface of the bracket being inclined, there being in the wall a series of equidistantly spaced perforations parallel with the upper surface thereof and notches sunk into the lower edge of said flange in axial alignment with said perforations to form therewith transverse passages through the bracket, an upper bracket having a groove at the bottom thereof of a size slidably to receive therein the flange of the lower bracket, rollers on said upper bracket adapted for riding in said beam, there being a series of similar notches sunk into the bottom surface of the upper bracket coplanar with the passages through the lower bracket but differently spaced apart, and a key insertable through any one of said passages and any one of said notches brought into axial alignment therewith.

2. A door hanger for supporting a door within a frame having a channeled beam mounted therein, said door hanger including a lower bracket having a base mountable on top of the door and a wall rising from said base, the upper end of said wall being folded to form a pendent flange parallel with the wall, the upper surface of the bracket being inclined, there being in the wall a series of equidistantly spaced perforations parallel with the upper surface thereof and notches sunk into the lower edge of said flange in axial alignment with said perforations to form therewith transverse passages through the bracket, an upper bracket having a groove at the bottom thereof of a size slidably to receive therein the flange of the lower bracket, rollers on said upper bracket adapted for riding in said beam, there being a series of similar notches sunk into the bottom surface of the upper bracket coplanar with the passages through the lower bracket but differently spaced apart, the lower portion of the hanger being offset to position the interengaging portions of the two brackets directly below the rollers, and a key insertable through any one of said passages and any one of said notches brought into axial alignment therewith.

3. A door hanger for supporting a door within a frame having a channeled beam mounted therein, said door hanger including an upper bracket, rollers on said bracket adapted to ride on said beam, the lower end of the bracket being bent to form an inclined bottom wall having a flange rising therefrom, the upper edge of said flange being correspondingly inclined and somewhat upwardly curved from both ends toward the center thereof, there being a series of notches sunk into the bottom surface of the bracket, a lower

bracket adapted to be mounted on and to rise from the top of a door, the upper end of said lower bracket being bent to form a flat top wall and a flange downwardly extending therefrom, the top wall being inclined to ride on the top edge of upper bracket flange, there being in the lower bracket a series of perforations coplanar with the notches of the upper bracket but differently spaced apart and notches sunk into the lower edge of the lower bracket flange in axial alinement with said perforations, the lower portion of the upper bracket being offset to position the interengaging portions of the two brackets directly below the rollers, and a key insertable through any one of said lower bracket passages 15 and anyone of said upper bracket notches.
